HIGH FREQUENCY ELECTRIC DISCHARGE DEVICE

Filed Nov. 13, 1942

Fig.1.

UNITED STATES PATENT OFFICE

2,406,277

HIGH-FREQUENCY ELECTRIC DISCHARGE DEVICE

Ralph J. Bondley, Scotia, N. Y., assignor to General Electric Company, a corporation of New York

Application November 13, 1942, Serial No. 465,424

15 Claims. (Cl. 250—27.5)

1

My invention relates to high frequency electric discharge devices and more particularly to ultra high frequency magnetrons of the space resonant type.

In electric discharge devices of the magnetron type, it is of considerable importance to provide structure which permits the establishment of the desired electrostatic and magnetic fields of desired intensity and configuration, and it is also important that the supporting structure be capable of withstanding voltage gradients of appreciable magnitude to obtain a power output commensurate with the size of the equipment. Furthermore, it is of considerable consequence to position and arrange the elements and supporting structure therefor so that the operation of the discharge device does not cause the deposition of a layer of conductive material on the insulating parts, which would cause the discharge device to become inoperative after a short period of operation.

In accordance with the teachings of my invention described hereinafter, I provide new and improved construction for an ultra high frequency magnetron which not only affords the desired insulating qualities of the structure but also minimizes heat transfer between elements thereof.

More particularly, I provide new and improved structure for an ultra high frequency magnetron of the type disclosed and broadly claimed in a copending patent application Serial No. 447,903 of Elmer D. McArthur, filed June 22, 1942, and which is assigned to the assignee of the present application.

It is an object of my invention to provide a new and improved ultra high frequency electric discharge device.

It is another object of my invention to provide a new and improved structure for supporting an electrode of an ultra high frequency magnetron of the space resonant type.

It is a further object of my invention to provide a new and improved cathode supporting structure for an ultra high frequency magnetron wherein the associated insulating means is protected by preventing the deposition of a conductive layer of material thereon incident to the evaporation of electrons from the electron emissive surface of the cathode.

Briefly stated, in the illustrated embodiment of my invention I provide a new and improved cathode supporting structure for an ultra high frequency magnetron which comprises a rigid concentric cable construction which extends through one of the associated magnetic pole pieces. The

2

inner conductor of the concentric cable extends through a cylindrical cathode and serves as a support for a shielding means, or member, which is positioned between the anode structure and the other associated pole piece. The insulating means which supports the rigid cable construction is displaced an appreciable distance from the end of the pole piece, thereby reducing the possibility of establishing any conductive layer thereon, and the outer conductor of the concentric cable is joined to the cylindrical cathode by means of a rigid metallic member which serves to shield the insulator. I also provide an improved structure for joining the cathode to the concentric cable whereby the heat transfer between the cable and the cathode is minimized.

For a better understanding of my invention, reference may be had to the following description taken in connection with the accompanying drawing, and its scope will be pointed out in the appended claims. Fig. 1 diagrammatically illustrates an embodiment of my invention as applied to an ultra high frequency magnetron of the space resonant type employing a pair of permanently magnetized pole pieces, and Fig. 2 is a plan view of the anode structure. Figs. 3 and 4 diagrammatically illustrate an alternative cathode supporting structure.

Referring now to Fig. 1 of the drawing, I have 30 there illustrated my invention as applied to an electric discharge device, such as an ultra high frequency magnetron, including an elongated cylindrical container, the lateral wall structure of which is provided by a single metallic tube 1 which 35 consists of a ferromagnetic material such as cold rolled steel, or the like. The ends of the container or tube 1 are closed by flanged members 2 and 3 which are welded or otherwise hermetically joined to the inner surface of tube 1. The outer surface 40 of the envelope may be provided with a plurality of radially extending fins (not shown) for the purpose of dissipating heat.

Within the container and approximately at its central region there is provided an anode structure 4 shown in detailed plan view in Fig. 2. The anode structure 4 is preferably of circular configuration provided with an enlarged central opening 5 and a plurality or series of smaller openings 6 arranged symmetrically about the 45 central opening. The central opening is joined to the openings 6 by means of radially extending slots 7.

The anode structure 4, which preferably consists of copper, is supported by being brazed to 50 the interior wall of tube 1. To facilitate the braz-

ing operation, small channels 8 are cut in the outer periphery of the structure and these are used to receive rings of brazing material applied before the anode structure is inserted within the tube 1. A relatively large circumferentially extending channel 9 serves to reduce the overall weight of the anode structure.

Within the opening 5 of the anode structure there is provided a thermionic cathode such as an indirectly heated cathode comprising a metallic sleeve 10 of nickel or other suitable material, and which is coated externally with a suitable activating material such as barium oxide. Within the sleeve 10, there is provided a filamentary cathode heating element 11 by which the cathode is maintained at an emissive temperature.

In operation of the device, a space charge is assumed to be developed in the space defined between the cathode sleeve 10 and the surrounding anode structure by the application of a suitable potential impressed therebetween. The electrons which compose this space charge are given a spiral or orbital motion by a magnetic field produced by means to be described presently, and the resultant oscillation, or oscillations, about the cathode produce excitation of the anode structure at its resonant frequency or harmonics thereof. The function of the anode structure may be explained from a point of view that it is made up of a plurality of mutually coupled units in each of which the inductance is provided by the wall surface of the openings 6, and the capacitance is provided by the opposite surfaces of the associated slots 7. Assuming this point of view, it will be observed that the operating frequency is in a large measure determined by the dimensions of the openings 6. In order to provide a magnetic field of sufficient intensity to permit the apparatus to function in its intended fashion, there are provided within the tube 1 tapered magnetic pole pieces 12 and 13, which may be permanently magnetized, and which are directed axially of the tube 1 and which extend in close proximity to the anode structure 4.

To assure the existence of a magnetic field of desired intensity when the pole pieces 12 and 13 are permanently magnetized, these members should be constructed of a magnetizable material or structure having a high coercive force and a high energy factor. One of the materials used in this connection is that alloy, or group of alloys, of aluminum, nickel and cobalt. For example, one type of alloy which may be used for this purpose is that described in the Mishima Patents 2,027,994 to 2,028,000. To provide a low reluctance connection between the base extremities of the respective pole pieces 12 and 13 and the lateral wall or tube 1, the pole pieces may be respectively seated upon relatively thick disc-like members 14 and 15 consisting of a ferromagnetic material such as steel. For the purpose of securing the pole pieces firmly to these base members, use may be made of clamping rings 16 and 17 which are slipped over the pole pieces and welded to the base members. Accurate spacing of the pole pieces 12 and 13 with reference to the anode structure may be obtained by the use of spacing rings 18 and 19 used in the manner indicated. As shown in Fig. 1, each of these rings is interposed between one surface of the anode structure and a surface of apertured discs 20 and 21, each disc in turn being in abutment with an appropriately formed shoulder 22 and 23 provided by the adjacent pole piece.

To permit the evacuation of all parts of the container, it is necessary to provide suitable passageways connecting the various sections or elements. For this purpose the disc-like members 14 and 15 may be provided with radially extending slots 24 and 25, respectively. In this manner, the longitudinal openings of the magnetic pole pieces 12 and 13, to be described presently, are in communication with the outside surface of the pole pieces to facilitate evacuation of the container. Of course, the apertures in discs 20 and 21 also serve as communicating paths for the same purpose. An evacuation or exhaust tubulation 26 may be welded or otherwise sealed to the flanged member 3 at the base of the entire structure.

Where it is desired to employ the magnetic pole pieces 12 and 13, either singly or jointly, as supports for one of the cooperating electrodes of the discharge device, these pole pieces may be provided, respectively, with longitudinal openings or channels 27 and 28 which are preferably of circular cross section having ends thereof which terminate in faces 29 and 30 of the pole pieces.

I provide a rigid concentric cable structure which extends through one of these openings or channels, such as channel 27, to support the cathode structure in the desired spaced relation with the anode structure 4. The rigid cable construction may comprise an inner conductor 31 and an outer tubular conductor 32, both of which are preferably constructed of a refractory metal such as nickel or molybdenum, and which are maintained in the desired concentric spaced relation by means of a plurality of spaced insulators 33, 34 and 35.

I provide means for maintaining the rigid cable construction in position and which is displaced a sufficient distance from the cathode structure, or the pole face 29, in order that it is not subjected to the heat incident to the cathode. This structure may comprise an insulator 36 and is designed to afford a long leakage path. For example, the insulator may have the configuration illustrated including a restricted portion which engages the outer conductor 32 and wherein the long leakage path is provided by longitudinally extending parts to have a general H-shaped cross-section. Of course, inasmuch as insulator 36 serves as a support for the cable structure, it is apparent that the insulator closely engages the wall surface of channel 27.

As a means for supporting the cathode structure from the outer conductor 32, I provide a metallic electrostatic shielding member 37 having a flanged part of a diameter equal to or less than the diameter of opening 5, thereby shielding the insulator 36 and preventing the deposition of a conductive layer thereon which would otherwise occur incident to the evaporation of electrons from the emissive surface of the cathode sleeve 10. Member 37 is provided with an aperture within which an insulator 37' extends, thereby insulating and centering inner conductor 31. Member 37 may be welded or soldered to the outer conductor 32 and the entire assembly is arranged to minimize the heat transfer between the cathode and the concentric cable construction, particularly outer conductor 32. One way in which such heat transfer may be minimized is by the employment of a plurality of spaced metallic tabs 38 and 39 of relatively small dimension which are made integral with part 37 or which may be made separately and welded or otherwise joined

to the cathode sleeve 10 and part 37. These tabs are of sufficient size to afford the desired mechanical strength of the juncture but the size and number are chosen to prevent appreciable heat transfer from the cathode to the outer conductor 32.

Inner conductor 31 is connected to one terminal, such as the upper terminal, of the cathode heating element 11 and serves to supply current thereto, the lower terminal of the cathode heating element being conductively connected to the cathode sleeve 10 which constitutes a path for the cathode heating circuit which is completed through the flanged metallic member 37 and outer conductor 32. The lower extremity of the inner conductor 31 is centered and supported by a heat resistant insulator 40 positioned at the lower end of the cathode sleeve 10.

I also provide electrostatic shielding means, such as a metallic disc 41, supported by the inner conductor 31 which extends through insulator 40. This member serves to prevent the collection of electron current on the face of pole piece 13.

The concentric cable construction is provided with externally accessible terminals or lead-in wires 42 and 43 which are connected, respectively, to inner conductor 31 and outer tubular conductor 32 and are, of course, arranged to afford this connection by means of a sealing structure which may include a glass or vitreous seal 44 supported by a flanged metallic cylinder 45, the latter of which is welded or soldered to the member 2.

In order to facilitate the evacuation of the space defined by the outer conductor 32, this element may be provided with a longitudinally extending opening or slot or slit 46. The tubular outer conductor 32 may be formed of sheet metal and the ends of the plate from which it is formed not being joined.

Of course, it will be appreciated that I may employ a single opening, or a series of longitudinally disposed openings, in the tubular conductor 32 which will serve equally well for the purpose of providing a passage, or passages, for the evacuation of gas during the exhaust process.

Energy may be extracted from the space resonant region, or regions, by any suitable output electrode means which may take the form of a loop 47 constituting an extension of an inner conductor 48 of a concentric transmission line comprising the inner conductor 48 and a concentric outer conductor 49.

In operation, upon the application of a suitable unidirectional voltage between the anode structure and the cathode, the system in its entirety will be set into oscillation, the energization of the various space resonant regions, or cavities, defined by openings 6 and slots 7 being derived from the motion of the electrons constituting the space charge between the cathode sleeve 10 and the surface of the enlarged central opening 5 of the anode structure 4. The various space resonant regions are mutually coupled and the energy of these cavities may be supplied to an external utilization circuit through loop 47 and the concentric transmission line comprising conductors 48 and 49.

One of the principal advantages of an electric discharge device built in accordance with my invention is the ease of construction inasmuch as the coated cathode, particularly sleeve 10, may be welded to the cathode assembly as a final step in the construction thereof, thus eliminating the necessity for masking the magnetic pole pieces 12 and 13 and the other metallic parts of the

structure. The outer conductor 32 of the concentric cable construction, as mentioned above, by virtue of the slot 46 therein, permits ready escape of undesired gas from the inside of the cable during the exhaust operation.

Fig. 3 diagrammatically illustrates a modification of my invention showing another form of a cathode structure which is supported from the rigid concentric cable structure, and wherein corresponding elements have been assigned like reference numerals. In the arrangement of Fig. 2, the cathode is supported from the outer tubular conductor 32 by means of a metallic flanged eyelet 53 which is welded or soldered to an apertured metallic disc 51 and which is provided with an inserted insulator 52, shown in Fig. 4, which fits into the end of the tubular conductor 32 and through which the inner conductor 31 extends. The cathode sleeve 10 is supported by disc 51 by means of a plurality of appropriately spaced metallic tabs 53 which are welded or soldered to sleeve 10 and disc 51. In like manner, a metallic shielding member 54, preferably of disc form, completely closes the end of cathode sleeve 10 and is attached thereto by means of metallic tabs 55. In this modification of my invention, the inner conductor 31 does not extend through the lower shielding member, and the lower terminal of the cathode heating element 11 is conductively connected to inner conductor 31 at a point near the bottom of the space defined by sleeve 10.

The shielding members 51 and 54 serve to collect the electron current which would otherwise tend to travel axially along the electrodes of the discharge device to points substantially beyond the anode-cathode region.

Certain features of the electric discharge device shown in Fig. 1 including the metallic containing member and the permanently magnetized magnetic field members, are disclosed and broadly claimed in the aforesaid copending patent application of Elmer D. McArthur, Serial No. 447,903, filed June 22, 1942. Other features relating to certain improved aspects of the cathode support construction are disclosed and claimed in a copending application, Serial No. 465,401 of George M. White, filed concurrently herewith and which is also assigned to the assignee of this application.

While I have shown and described my invention as applied to a particular device embodying various elements diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

- An electric discharge device comprising a plurality of cooperating enclosed electrodes including a thermionic cathode having a heating element and an anode structure surrounding said cathode, means for establishing a magnetic field comprising a magnetic pole piece substantially perpendicular to the plane of said anode structure, said magnetic pole piece having a channel extending longitudinally therethrough, a rigid concentric cable structure supporting said cathode and for supplying current to said heating element and comprising an inner conductor and a tubular metallic outer conductor and including a plurality of spaced insulating means therebetween, and an insulator displaced from the end

of said channel facing said anode structure and supporting said cathode structure.

2. An electric discharge device comprising a plurality of cooperating enclosed electrodes including a thermionic cathode, an anode structure surrounding said cathode, means for establishing a magnetic field comprising a magnetic pole piece substantially perpendicular to said anode structure, said pole piece having therein a channel extending longitudinally therethrough, a concentric cable structure supporting said cathode in spaced relation with respect to said anode structure and comprising an inner conductor and a tubular metallic outer conductor and having a plurality of longitudinally displaced insulating means maintaining said inner and outer conductors in spaced relation, and an insulator displaced from the end of the channel terminating in the pole face of said pole piece and supporting said cable structure.

3. An electric discharge device comprising a plurality of cooperating enclosed electrodes including a thermionic cathode and an anode structure surrounding said cathode, means for establishing a magnetic field comprising a magnetic pole piece, said magnetic pole piece having therein a channel extending longitudinally therethrough, and a concentric cable structure supporting said cathode comprising an inner conductor and a tubular metallic outer conductor including a plurality of spaced insulating means maintaining the conductors in spaced relation.

4. An electric discharge device comprising a plurality of cooperating enclosed electrodes including a thermionic cathode having a heating element, an anode structure surrounding said cathode, means for establishing a magnetic field comprising a magnetic pole piece substantially perpendicular to the plane of said anode structure, said magnetic pole piece having a channel extending longitudinally therethrough, and a concentric cable structure supporting said cathode comprising an inner conductor and a tubular metallic outer conductor and a plurality of spaced insulating means maintaining the inner and outer conductors in spaced relation.

5. An electric discharge device of the magnetron type comprising a plurality of cooperating electrodes including a cathode and an anode structure, means for establishing a magnetic field and comprising a magnetic pole piece lying substantially perpendicular to the plane of said anode structure and having a longitudinal channel therethrough, an enclosure around said electrodes and the means for producing the magnetic field, means supporting said cathode in spaced relation with respect to said anode structure and including a rigid concentric cable structure having an inner conductor and an outer tubular conductor, said tubular conductor being attached to said cathode and the inner conductor extending through the cathode, and an electron shielding means supported by said inner conductor.

6. An electric discharge device comprising a plurality of cooperating enclosed electrodes including a cylindrical thermionic cathode having a heating element and an anode structure, means for establishing a magnetic field comprising a magnetic pole piece substantially perpendicular to the plane of said anode structure, said magnetic pole piece having a cylindrical channel extending longitudinally therethrough, means comprising a concentric cable structure supporting said cathode and for supplying current to said heating element and including an inner con-

ductor and a tubular metallic outer conductor, a flanged metallic member on one side of said anode structure and connected to and supported by said outer conductor and having a diameter equal to or less than the diameter of the anode-cathode region, said inner conductor extending through said cathode, and an electron shielding member supported by the extending portion of said inner conductor.

7. An electric discharge device comprising a plurality of cooperating enclosed electrodes including a cylindrical thermionic cathode having therein a heating element and an anode structure substantially surrounding said cathode, a pair of magnetic pole pieces substantially perpendicular to the plane of said anode structure and positioned on opposite sides thereof, one of said pole pieces having a cylindrical channel extending longitudinally therethrough, a concentric cable structure positioned within the channel of one of said pole pieces supporting said cathode in spaced relation with said anode structure and comprising an inner and outer metallic conductor, insulating means displaced from the end of said one channel supporting said outer conductor, a metallic flanged member connected to said outer conductor and said cathode and having a diameter less than that of said channel, and an electron shielding metallic member positioned between said anode structure and the other pole piece, said inner conductor extending through the cylindrical cathode and providing a support for said last mentioned member.

8. An electric discharge device comprising a plurality of cooperating enclosed electrodes including a thermionic cathode having a heating element and an anode structure substantially surrounding said cathode, means for establishing a magnetic field comprising a magnetic pole piece substantially perpendicular to the plane of said anode structure, said magnetic pole piece having a channel extending longitudinally therethrough, a concentric cable structure supporting said cathode and for supplying current to said heating element and including an inner conductor and a tubular outer metallic conductor, an insulator within said channel and displaced from the end thereof facing said cathode and supporting said cable structure in said channel, and a metallic member connected between said cathode and said outer conductor to minimize heat transfer between said cathode and said outer conductor.

9. An electric discharge device comprising a plurality of cooperating enclosed electrodes including a thermionic cathode having a heating element, an anode structure surrounding said cathode, means for establishing a magnetic field comprising a magnetic pole piece substantially perpendicular to the plane of said anode structure, said magnetic pole piece having a channel extending longitudinally therethrough, and a concentric cable structure supporting said cathode comprising an inner conductor and a tubular metallic outer conductor and insulating means maintaining the inner and outer conductors in spaced relation, said outer tubular conductor being provided with an opening to facilitate evacuation of said discharge device.

10. An electric discharge device comprising a plurality of cooperating electrodes including a substantially cylindrical cathode having a heating element and an anode structure substantially surrounding said cathode, a pair of magnetic pole pieces spaced on opposite sides of said anode structure, said pole pieces each having there-

in a channel positioned longitudinally the pole piece, means positioning said cathode and for supplying heating current to said heating element comprising a rigid concentric cable construction including inner and outer conductors extending through the channel of one of said pole pieces and having externally accessible terminals, means connecting the outer conductor of said cable to one end of said cathode, and means positioned in said channel and engaging said outer conductor to position said cable with respect to said anode structure.

11. An electric discharge device comprising a plurality of cooperating electrodes including an elongated cathode and an anode structure surrounding said cathode, a pair of magnetic pole pieces spaced on opposite sides of said anode structure, said pole pieces each having therein a channel positioned longitudinally of the pole piece, and means positioning said cathode comprising a concentric cable construction attached to said cathode and extending through the channel of one of said pole pieces and an insulator in said channel and engaging said cable to center said cable, said insulator having a creepage path from said cable to the wall of said channel substantially greater than the shortest distance between said cable and said wall.

12. An electric discharge device comprising a plurality of enclosed cooperating electrodes including a thermionic cathode including a heating element and an anode structure surrounding said cathode, a pair of magnetic pole pieces spaced on opposite sides of said anode structure and each having therein a channel of circular cross section positioned longitudinally of the pole piece, means supporting said cathode and for supplying current to said heating element comprising a rigid concentric cable construction including an inner and outer conductor extending through the channel of one of said pole pieces, and an insulator fitted in the channel of said one pole piece and engaging said outer conductor to center said cable and thereby to center said cathode with respect to said anode.

13. An electric discharge device comprising a plurality of cooperating electrodes including a cylindrical thermionic cathode and an anode structure of annular form having a circular center opening within which said cathode is located, a pair of magnetic pole pieces spaced on opposite sides of said anode structure, said pole pieces each having therein a channel positioned

longitudinally of the pole piece, means positioning said cathode comprising a concentric cable construction extending through the channel of one of said pole pieces and comprising an inner conductor and a concentric outer conductor and insulating means therebetween, an insulator positioned in the channel of said one pole piece within the vicinity of the pole face supporting and centering said cable, a cathode heating element surrounded by said cylindrical cathode and having one terminal electrically connected to said inner conductor, and a metallic member connected to the other terminal of said cathode heating element and said outer conductor and spaced between said cathode and said insulator to prevent the condensation of conductive material on said insulator.

14. An electric discharge device comprising a plurality of cooperating electrodes including a thermionic cathode having an emissive surface and an anode structure surrounding said cathode, a pair of magnetic pole pieces spaced on opposite sides of said anode structure, said pole pieces each having therein a channel positioned longitudinally of the pole piece, means positioning said cathode comprising a concentric cable construction extending through the channel of one of said pole pieces and attached to said cathode, an insulator positioned in the channel of one of said pole pieces within the vicinity of the pole face, and shielding means positioned between said cathode and said insulator to prevent the deposition of conductive material on said insulator.

15. An electric discharge device comprising a plurality of cooperating electrodes including a thermionic cathode having an emissive surface and an anode structure surrounding said cathode, a pair of magnetic pole pieces spaced on opposite sides of said anode structure, said pole pieces each having therein a channel positioned longitudinally of the pole piece, means positioning said cathode comprising a concentric cable construction extending through the channel of one of said pole pieces and attached to said cathode, an insulator positioned in the channel of one of said pole pieces within the vicinity of the pole face, and conductive means constituting a part of said cathode shielding said insulator to prevent the deposition of conductive material thereon.

RALPH J. BONDLEY.
